ELECTRON DISCHARGE TUBE

Henny Cohn, Berlin, Germany, assignor to Telefunkens Gesellschaft für Drahtlose Telegraphie m. b. H., Berlin, Germany, a corporation of Germany

Application February 23, 1934, Serial No. 712,553
In Germany February 22, 1933

10 Claims. (Cl. 250—27.5)

(Granted under the provisions of sec. 14, act of March 2, 1927; 357 O. G. 5)

The present invention is concerned with an electrode system in which, apart from a main discharge gap, there is provided an auxiliary discharge gap independent of the former.

Preference is being given nowadays in the art of radio receivers to circuit schemes in which such volume fluctuations as are occasioned by atmospheric phenomena are compensated. For this purpose the aggregate gain of the receiver is usually so adjusted by the variation of the grid biasing voltage of a radio frequency amplifier tube as a function of the prevailing incoming field intensity that the audio frequency output potential remains stable and unvaried. The regulator voltage consists of a rectified carrier wave of the particular transmitter station that is being received, derived from the plate circuit of a rectifier, generally the demodulator. In order that separate compensator batteries may be dispensable, recourse is had for rectification to two-electrode tubes or diodes which operate without any additional direct voltage or at most with only low voltage. Inasmuch as the discharge current of such a rectifier gap is low it is feasible to combine the second electrode system constructionally inside a common glass bulb with the tube electrodes of the same circuit scheme or another consecutive tube.

In the embodiments of combination or compound tubes of the said sort heretofore used the cathode is extended, so that it protrudes beyond the electrode system, and over this free or projecting end are shifted one or two anodes, depending upon whether half-wave or full-wave rectification is desired. This type of construction involves the drawback that the cathode must be extended, requires more heating energy, and that supplementary shielding means which tend to make the construction essentially more expensive, are absolutely necessary in order that the rectifier system may be uncoupled electrically in reference to the main discharge path. Another point that must be kept in mind is that owing to the greater length of the electrode structure the tube will evidence a greater tendency to develop microphonic noises.

Now, the present invention discloses an electrode system which represents a simple solution of this problem. The invention is predicated upon the fact that the lateral end face of an indirectly heated cathode is made emissive and utilized as the source of an auxiliary discharge. The indirectly heated cathode consists of a ceramic body in the interior of which the heater proper is accommodated. The outer surface of

the insulation body is provided with a metallic coating which is made either by the application of a coat of metal or else by shifting a metallic tube or sleeve thereover. The electron-emissive coat is then applied by any of the methods known in the art. According to this invention the end surface of the cathode support is also metallized and thus rendered electron-emissive, and opposite the same a small anode is mounted.

A number of embodiments are shown schematically in Figs. 1 to 6 of the accompanying drawing.

Referring to Fig. 1, K denotes an indirectly heated cathode of cylindrical form, G is the grid electrode, and A the anode of a triode system. The end face K' of the cathode is also rendered emissive, and face to face therewith there is mounted an auxiliary anode H. In order that the capacity of the auxiliary electrode in reference to the amplifier system may be minimized, the auxiliary electrode shown in Fig. 2 may consist of a wire H' which is positioned coaxially with respect to the cathode. In this case, additional shielding will not be necessary.

But if some shielding is inevitable, this can be provided by the simple construction disclosed in Fig. 3, wherein R denotes the tiny insulation tube containing the heater, upon which is shifted in the usual way a slender metal tube or sleeve M which is coated with an electron-emissive layer O. At the end facing the auxiliary anode H the metal tube has a flange F on which is fastened a metallic shield S, for instance, by welding. In order to perfect the shielding, the said shield S may also be provided with an annular extension S'. Directly over the end of the small insulation tube, the shield S is activated by coating it with a small quantity of emissive substance O'.

Fig. 4 discloses a construction wherein the shield S' is united in a simple way with an insulating disc which serves to support and space the several electrodes. In this modification K, G, and A are respectively the cathode, grid and anode of the electrode system, said elements being supported and suitably spaced by the aid of an insulation disc J of ceramic or other suitable material. The upper face of disc J adjacent the auxiliary anode H'' is provided with a metallic coat or film O' which is united with the cathode coat, and which may consist of a metal foil, of a layer made by a spray process, or the like. Of course, care must be taken so that the grid and anode support wires T will not contact with the metal shield S' in order to avoid short-circuiting between the electrodes.

Since the end of the cathode is naturally sub-

55

jected to more marked cooling, and since this effect is increased on account of the metal shield associated therewith, it may, under certain circumstances, be necessary and convenient to adopt 5 ways and means adapted to insure stronger heating of the cathode end. Fig. 5 discloses a suitable method by which this may be accomplished, the turns of heater wire D which are disposed within the insulation tube B being wound somewhat more closely at one end than in the middle of the 10 cathode.

The idea underlying the present invention, of utilizing a cathode portion which is unused for the major discharge path by conveniently mounting means for an auxiliary discharge path, will be found useful in different ways in connection with other forms of cathode. For instance, flat cathodes are known in the art whose ceramic body is of rectangular form. The suggestion has been 15 made with a view to insuring a homogeneous field shape to activate only the broad sides of such a cathode body, while leaving the edges and narrow sides or faces thereof non-emissive. In cathodes of this type one or both narrow sides may be 20 utilized to act as cathode areas for an auxiliary discharge gap or gaps. Fig. 6 shows a cross-section through such an electrode system, where C represents the cathode or the carrier member for the cathode, G the grid electrode consisting of 25 a metal gauze or fabric which is laid about two support or stay wires T and is fastened thereto. The anodes A are shown arranged in parallel planes although other anode forms may be used. The two broad sides of the cathode are provided 30 with electron-emissive coats C', while the narrow sides are coated with active substance as indicated at C'' for supplying the electrons for the auxiliary discharge gaps. The auxiliary anodes P may, for instance, be made from wires or narrow strips of sheet material, and these may be 35 connected in parallel for half-wave rectification or else may be connected to operate as push-pull or full-wave rectifiers.

What I claim is:

- 45 1. An electron discharge tube comprising a unitary cathode structure provided with arcuate and planar electron emitting surfaces and an electron collecting electrode cooperating with each of said emitting surfaces to form therewith a plurality of independent discharge paths.
- 50 2. An electron discharge tube comprising a thermionic cathode axially disposed therein and having a plurality of surfaces, one of which emits electrons radially and another of which emits electrons axially, and a plurality of electrodes cooperating with said cathode surfaces to form independent discharge paths.
- 55 3. An electron discharge tube comprising a cathode axially disposed therein and having a plurality of surfaces, one of which emits electrons radially and another of which emits electrons axially, a plurality of electrodes cooperating with said cathode surfaces to form independent discharge paths, and an electrostatic shield interposed between said discharge paths.
- 60 4. An electron discharge tube comprising a cathode axially disposed therein and having a

plurality of surfaces, one of which emits electrons radially and another of which emits electrons axially, a plurality of electrodes cooperating with said cathode surfaces to form independent discharge paths, and an electrostatic shield, conductively connected to the cathode, interposed between said discharge paths. 5

5. An electron discharge tube comprising an electron emitting electrode having arcuate and planar surfaces, an amplifier anode cooperating with said arcuate emitting surface and forming therewith the principal discharge path, and a rectifier anode cooperating with the planar emitting surface and forming therewith an auxiliary discharge path which is substantially at right 15 angles to the principal discharge path.

6. An electron discharge tube comprising an electron emitting electrode having arcuate and planar surfaces, an amplifier anode cooperating with said arcuate emitting surface and forming 20 therewith the principal discharge path, a rectifier anode cooperating with the planar emitting surface and forming therewith an auxiliary discharge path which is substantially at right angles to the principal discharge path, and an electro- 25 static shield, conductively connected to the emitting electrode interposed between said discharge paths.

7. An electron discharge tube comprising a thermionic cathode having a substantially cylindrical electron emitting surface and a planar emitting surface, and an electron collecting electrode independently cooperating with each of said emitting surfaces. 30

8. An electron discharge tube comprising an 35 electron emitting member having an axially disposed metallic sleeve coated with an electron emissive substance, a shield member connected to said metallic sleeve and projecting in a plane perpendicularly to the sleeve axis, a plurality of 40 electrodes concentrically arranged about said metallic sleeve and disposed to one side of said shield, and an auxiliary electrode mounted on the other side of said shield and close to the metallic sleeve. 45

9. An electron discharge tube comprising a metallic sleeve coated on its outer surface with an electron emissive substance, a metal disc member laterally disposed over the edge of the metallic sleeve and connected thereto, the metal disc being 50 provided on its external side with a coating of electron emissive substance, an electrode mounted on that side of the metal disc having the electron emissive coating, and a plurality of electrodes mounted on the other side of the metal disc and 55 surrounding the coated metallic sleeve.

10. An electron discharge tube comprising a cylindrical cathode, grid and anode electrodes surrounding the cathode, an insulating disc mounted at one end of said electrodes, a shield 60 supported on said insulating disc and having that portion thereof which is in alignment with the cathode coated with an electron emissive substance, and an auxiliary electrode positioned to cooperate with said coated portion of the shield. 65
